CABINET CONSTRUCTION FOR AIR
CONDITIONING UNIT

Richard E. Allender, Davenport, Iowa, and Dale L. Selhost, Rock Island, Ill., assignors to American Air Filter Company, Inc., Louisville, Ky., a corporation of Delaware

Filed Aug. 7, 1964, Ser. No. 388,224
5 Claims. (Cl. 312—213)

This invention relates to an improved cabinet construction for air conditioning units of the fan-coil type. Such units are especially suitable for offices, hallways, lobbies and other spaces in institutional, hospital and commercial buildings, and are frequently seen there as well as in rooms in hotels and motels. They are used to heat, ventilate, and/or cool the served space.

There are a number of more or less mandatory requirements in the provision of a satisfactory fan-coil unit, and to some degree these requirements concern themselves with the cabinet structure. The cabinets should be sufficiently sturdy and rigid as to stand normal abuse. They should have a pleasing appearance since they must blend in or alternatively highlight the decor of the served space. The general structure of the cabinets should be such that they can be efficiently produced, since they are sold in a highly competitive market. Hence they should include relatively inexpensive parts to the extent possible.

One of the most important requirements, and one directly related to ultimate cost of the unit, is that the structural arrangement of the unit should be such as to readily lend itself to application in various arrangements. For example, the range of models which may be required of fan-coil units includes, but is not limited to, floor, floor recessed, wall, wall recessed, inverted wall, inverted wall recessed, ceiling, ceiling recessed, and built-in models. Further, within the limits of a particular model, various arrangements may be prescribed for where the air to be treated is to enter the unit and where it is to leave the unit.

As one example, with a wall-hung type of unit any one of four different air paths may be specified. Recirculation air may be required to be drawn into the cabinet through the bottom, or alternatively through the lower part of the front face. The air being discharged back into the room may be required to be delivered out of the top of the unit or, alternatively, out of the upper part of the front face. Consequently, it will be apparent that in connection with this single model, any one of four different panel arrangements may be required for a particular installation. Different panel arrangements for varying the location of the recirculation air inlet and discharge air outlet are also required for other models to an equal or lesser degree.

The foregoing requirements are admirably met, we believe, by units incorporating our invention. As is conventional, we provide the principal operating parts of a fan-coil unit such as the coil, fans, and fan motor, dampers and the like in a central core or center compartment structure having substantially the same box-like exterior form in all models. The opposite ends of the core portion are provided with vertical partitions which define the width of the central core portion and which are tied to each other by internal structure extending between the opposite vertical partitions. The interior structure of the core does not form a part of this invention and will therefore not be described in any detail.

In accordance with the invention, the panel parts which serve as the finished surfaces of the cabinet casing are so constructed that they perform a framing function with posts and braces and the like substantially eliminated outside of the central core space. In a word, the outer

2

panels of the cabinet are not simply hung on a frame, but serve as part of the frame itself.

The outer panels for carrying out this concept generally include opposite end panels and panels for the other three normally exposed faces of the cabinet (i.e., front, top, and bottom). The end panels are adapted to be mounted in outwardly-spaced and parallel relation to the respective opposite vertical partitions of the core so as to form end compartments between the vertical partitions and the end panels. The end panels are each provided on their inner faces with flanges inset from at least the top, bottom and front edges to form inside corners along these edges. The flanges are inset to a degree as to be aligned with the corresponding edges of the vertical partitions when the end panels are mounted. End panels so formed are very sturdy and rigid since the inset flanges not only serve as fastening elements but also stiffen the end panels.

The panels for the other faces of the cabinet extend between the opposite end panels with their ends received by the inside corners of the end panels. Some of the face panels are secured to both the end panels and the vertical partitions while others may be secured only to the vertical partitions.

In accordance with a principal feature of the invention, at least one of the face panels is a corner panel having equal width leg portions. One of the leg portions is provided with an open-work grille, and the other is imperforate. The corner panel is attached over one of the corners formed by the front and an adjacent face so that the variations in inlet and outlet location requirement may be readily accommodated. The corner panel may not only be used on many different models but may also be reversed in its particular location.

The overall construction of the cabinet casing is such as to accommodate the use of certain common parts in various models and to also facilitate assembly and servicing disassembly as will more fully appear from the following.

The invention will be explained in somewhat more detail in connection with the accompanying drawing wherein:

FIGURE 1 is a perspective view of a floor model fan-coil unit embodying the invention;

FIGURE 2 is a partly exploded isometric view of the FIGURE 1 model;

FIGURE 3 is a partly exploded isometric view of a wall model fan-coil unit illustrating certain differences and similarities between the floor model and the wall model;

FIGURE 4 is a sectional view through a corner panel, this view corresponding to one taken along the line 4—4 of FIGURE 2; and

FIGURE 5 is a sectional view through a rear top panel corresponding to one taken along the line 5—5 of FIGURE 2, with the position of a corner panel in installed relation shown in broken line outline.

The exterior of the floor model cabinet of FIGURE 1 does not readily disclose the interior separation of the unit into a center compartment and a pair of opposite end compartments separated from the center compartment by vertical partitions. However, the division is perceptible at the bottom of the unit where the horizontal opening at the bottom is defined at the ends by the vertical partitions.

The principal visible parts of the cabinet casing of FIGURE 1 include: a pair of end base sections 10 which rest on the floor and underlie the end compartments; a pair of lower corner filler members 12; a bottom plate 14 which lies flat on the floor under the center compartment, and which has its left edge secured to left-hand vertical partition and its right edge secured to right-hand

vertical partition 16; front panel 18 secured by a pair of fasteners 20 to the vertical partitions therebehind; a right end panel 22; a left end panel 24; a rear top panel 26; and a top corner panel 28 which is a one-piece panel having equal dimension leg portions disposed in planes at right angles to each other, the one leg portion 30 shown in FIGURE 1 as extending across the upper front face of the cabinet having an imperforate surface, and the other leg portion 32 extending across the top front part of the cabinet being provided with an open-work grille surface.

In a floor model as shown in FIGURE 1, recirculation air is drawn into the lower front opening defined below the front panel 18 and above the base plate 14, and between the left and right vertical partitions. After being treated in the unit, the air is discharged back into the room through the grille portion 32 of the corner panel 28.

In FIGURE 2 the interior structure of the cabinet is generally exposed along with some detail of the panel construction. Here both the front panel 18 and the upper front corner panel 28 are shown in exploded relation to the rest of the cabinet. The operating parts for the center compartment such as the fans and fan motor, the heat exchanger, drain pan arrangement if used, and air filter are not shown. This exposes the rear plate 34 covering the back of the unit between the right vertical partition 16 and left vertical partition 36. The right-hand and left-hand end compartments 38 and 40 respectively are also clearly shown.

The end panels 22 and 24 are of identical form so that they are interchangeable. Each is preferably formed from a single piece of sheet metal to include top, front and bottom flanges 42, 44 and 46 inset from the respective edges along the inner face of the end panel, and a rear edge flange 48 flush with the rear edge of the panel. The inset is generally equal to the thickness of the top rear panel 26 and the common thickness of the front panel 18. The overall dimensions of the end panels are such that when the end panels are mounted the top and front inset flanges 42 and 44 will be aligned with the peripheral flanges 50 along the top and front of the vertical partitions 16 and 36. The end panels are secured in outwardly spaced relation from the vertical partitions at the top by the rear top panel 26 and at the bottom by the base members 10. The ends of the rear top panel are received by the inside corners partially formed by the top inset flanges 42 of the end panels. The end panel bottom flanges 46 are secured to the bight portions of the underlying base members 10.

The upper corner panel 28 shown in FIGURES 2 and 4 is of the style in which the louvers are stamped out of sheet metal rather than being built up from individual members. Thus it may be fabricated from a single sheet of metal. A built-up corner panel using bars rather than stamped louvers may be used when the varied appearance is desired.

It will be observed from FIGURE 4 that the general exterior shape of the corner panel is symmetrical about an apex line dividing the two leg portions. Also, along each of the opposite longitudinal edges inside corner or recessed flanges 52 and 54 are provided equidistant from the apex of the corner panel. Thus, the corner panel 28 of FIGURE 2 may be turned end-for-end from its position shown, and assembled so that the grillework portion 32 would lie along the front face while the imperforate leg portion 30 would lie along the top face of the unit.

The relationship of the corner panel 28 to the rear top panel 26 as they are assembled on the unit is shown in FIGURE 5. There a fragmentary portion of the corner panel 28 is shown in broken-line form to illustrate how it fits with the rear top panel. As shown, inwardly-directed flange means 56 and 58 are provided to underlie each of the longitudinal edges of the rear top panel. At each end of the panel, an additional flange 60 is provided which is bent under and is deliberately spaced farther from the upper surface of the panel than the other flanges

56 and 58. This provides a space between the flange 56 and end panel flange 42 into which flange 52 of the corner panel fits when the end flange 60 rests upon and is secured to the inset flange 42 of the end panel. This arrangement is used at both ends of the unit.

10 To hold the panels together, one sheet metal screw 61 (FIGURE 5) secures inset flange 42 and end flange 60 together, while another screw 63 secures inset flange 42 to flange 56 with the longitudinal flange 52 of the corner panel sandwiched in between. Additionally, both the top rear panel 26 and corner panel 28 are secured to the peripheral flange 50 of the vertical partitions where their common edges overlie the flanges 52.

15 After installation of the unit at the job site, the front panel 18 is the only panel that is normally removed from the unit in the field for servicing. Thus it is fastened by means which provide for its ready release. Specifically, a pair of projecting keepers 62 at the bottom edge of the front panel 18 catch behind the lower corner members 12, and the two fasteners 20 are then used to secure the upper edge of the front panel to the vertical partition flanges 50. The fastener screws 20 also pass through the illustrated holes in the flange 54 of the corner panel 28. It will be appreciated that when the front panel 18 is removed from the cabinet for servicing, the lower edge of the corner panel 28 is then unsecured. However, the remainder of the corner panel remains sufficiently well secured along its opposite edge.

20 FIGURE 3 shows a wall-hung model in which the parts which are the same as the parts of the floor model are given the same numeral even though they may be oriented and located differently. While there are numerous minor differences in parts, on the whole the differences are slight. Of course, since the unit is wall-hung rather than resting upon a floor, those base parts of FIGURE 2 are not present in FIGURE 3. Additionally, the end panels (both designated 70) are of greater height than those of FIGURE 2. However, in other respects the end panels are the same in that they are provided with inset flanges along the same edges, and rear flange is flush. Further, as in the case of the floor model, the end panels are universal in that they may be used at either end. An additional difference is that while the vertical partitions 72 and 74 for the wall-hung units are different with respect to the ledges for their interior parts, they are very similar to the floor model ones including having the peripheral flanges 76 to which the panel parts are fastened.

25 The wall model front panel 78 is generally the same as the front panel 18 of the floor model except for the addition of two more holes for additional fasteners 20 and the deletion of the keepers 62.

30 The wall-hung unit is provided with a rear bottom panel 26 as well as a rear top panel 26, both of which correspond exactly to the rear top panel for the floor model. Thus, the rear top and bottom panels of the wall-hung unit are not only interchangeable on a particular unit, but are also interchangeable with those used on floor models.

35 The same corner panels 28 are used for the upper front corner and the lower front corner of the wall-hung unit as are used for the upper corner of the floor model. The corner panels are not only universal in the sense of being used on various models, but are also reversible in a particular location to change the inlet, or outlet, location. For example, on the wall-hung unit, the recirculation air inlet may be on the bottom face or front face, and the air outlet may be either on the top face or the front face.

40 While the floor model usually has only a single corner panel as shown in FIGURE 2 mounted along the upper front corner, this panel may also be disposed to either discharge air out of the top or the front of the unit.

45 The wall and ceiling models both ordinarily use two corner panels along both front corners, and consequently, 50 with each model, any one of four different air paths may

be provided. Furthermore, if a model is shipped to the job site with the corner panels incorrectly disposed, they may be readily removed and reversed at the site.

Having described our invention we claim:

1. Air conditioning cabinet structure comprising: an interior, longitudinally extending, vertical, central compartment portion including opposite end vertical partitions; 5
a pair of opposite end panels adapted to be mounted in outwardly-spaced relation from said vertical partitions; 10
a plurality of panels at least one of which is connected to said vertical partitions, extending for substantially the length of said cabinet across said central compartment and between said end panels to cover the top face and at least one adjacent face other than an end face; 15
at least one of said panels being a one-piece member of right-angle shape in cross section so as to be adapted to seat upon a corner formed between the front face and an adjacent face other than an end face, said right-angle panel being provided with equal width and cross-sectional shape leg portions, one of which leg portions includes open-work grille portions therein, and the other of which is imperforate. 20
2. The construction of claim 1 wherein: each of said opposite end panels includes flanges projecting from the inner face thereof with the flanges associated with the front edge and adjacent edges being inset from said edges to form inside corners to 30 accommodate the ends of said panels extending between said end panels.
3. Air conditioning cabinet structure comprising: an interior central compartment portion defined at its ends by vertical partition members; 35
a pair of opposite end panels adapted to be mounted in outwardly-spaced relation from said vertical partition members, each of said end panels having flanges on their inner faces along the front and adjacent edges, inset to a degree as to be in alignment with the corresponding edges of said vertical partition members; 40
means connecting said end panels to said vertical partition members of said central compartment including at least one generally flat panel extending for the length of said cabinet with ends secured to said end panel inset flanges and intermediate points secured to said vertical partition members for support thereof; and 45
at least one panel generally co-extensive with the length of said cabinet and being of right-angle shape in cross section with equal width leg portions, one of said leg portions including open-work grille means and the other leg portion being imperforate.

4. The cabinet structure of claim 3 wherein: said angle panel includes outwardly-directed flange means along its opposite longitudinal edges; and said generally flat panel includes inwardly-directed flange means along its opposite longitudinal edges, and offset plane flange means at its ends, said angle and said flat panels being adapted to be butted together along respective longitudinal edges with an outwardly-directed flange of said angle panel being accommodated under an inwardly-directed flange of said flat panel.
5. Air conditioning cabinet structure comprising: a central compartment portion of generally right parallelepiped form having opposite end vertical partitions; a pair of opposite end panels for said cabinet, each end panel being adapted to be mounted in parallel, outwardly-spaced relation from said vertical partitions so as to form opposite end compartments between respective ones of said vertical partitions and said end panels, each end panel having an inner face provided with inwardly directed panel mounting flanges along at least two edges, said flanges being of an extent as to provide a portion thereof in substantial alignment with the corresponding edges of said vertical partitions when said end panels are mounted; panel means for substantially covering at least the front and one adjacent face, other than an end face, of said cabinet, all of said panel means being of a length to extend from end panel to opposite end panel, and to be received by said inwardly directed flanges; means for securing at least some of said panel means at their ends to said end panels, and at intermediate points to said vertical partitions; said panel means including at least one panel of angle-shaped cross section and equal width legs, one of said legs being imperforate and the other including open-work grille means, so that said angle-shaped panel may be selectively mounted to provide an opening along the front face or along an adjacent face of said cabinet.
